UNITED STATES PATENT OFFICE.

JOHN GOETTEL, OF BOSTON, MASSACHUSETTS, ASSIGNOR OF ONE-HALF TO
E. BERTRAM NEWTON, OF SAME PLACE.

BICYCLE.

SPECIFICATION forming part of Letters Patent No. 569,636, dated October 20, 1896.

Application filed March 21, 1896. Serial No. 584,339. (No model.)

To all whom it may concern:

Be it known that I, JOHN GOETTEL, residing in Boston, county of Suffolk, and State of Massachusetts, have invented an Improvement 5 in Bicycles, of which the following description, in connection with the accompanying drawings, is a specification, like letters on the drawings representing like parts.

This invention relates to bicycles, and has 10 for its object to improve the construction of the same in a manner as will be described.

In accordance with this invention the pedal-shaft has fast on it a driving-wheel of a construction as will be described, and the said 15 driving-wheel co-operates, as will be described, with a counter-shaft provided with a sprocket-wheel and connected by a link chain to a sprocket-wheel on the rear wheel of the bicycle. In order that the link chain may be 20 made of increased length, the hanger for the sprocket-shaft is located above the hanger for the pedal-shaft and is connected thereto, and the hanger for the pedal-shaft is also connected by substantially short brace-bars with 25 the rearwardly-extended wheel-supporting bars of the framework, as will be more specifically described.

Figure 1 represents in side elevation a safety-bicycle embodying this invention; Fig. 30 2, a detail, on an enlarged scale, of my improved driving mechanism; Fig. 3, a transverse section on the line A A, Fig. 2; and Figs. 4 and 5, details to be referred to.

Referring to Fig. 1, A represents the front 35 wheel, and A' the rear wheel, of a safety-bicycle having a framework A², which in its general construction approximates the framework commonly employed in safety-bicycles, but differs therefrom in providing between 40 the wheels A A' two hangers, one for the pedal-shaft a' and the other for a sprocket-wheel or counter shaft a², the hanger for the sprocket-wheel shaft being located above and in a substantially straight line with the saddle-supporting post or tube a³.

The hanger for the sprocket-wheel shaft a² has connected to it the rearwardly-extended brace rods or tubes a⁴, and the latter are, in accordance with this invention, connected by 50 short brace-rods a⁵ to the hanger for the pedal-shaft a'. By this construction and arrange-

ment the link chain a⁶ may be made substantially as long as that now commonly employed in the ordinary frame of safety-bicycle and better results are obtained than if the hanger 55 for the sprocket-wheel shaft were located in a horizontal line or behind the hanger for the pedal-shaft. The pedal-shaft a', in accordance with this invention, extends through the hub b of a driving-wheel of a construction as 60 will now be described, which driving-wheel consists, essentially, of a circular plate or disk b', provided with an annular rim b², and on its inner side near its circumference the said plate or disk is provided with a series of 65 projections b³, (shown best in Fig. 4,) each of the said projections being provided on its front face with an annular socket and with a centering stem or teat b⁴, projecting from the socket, beyond the outer edge of the same, as 70 clearly shown in Fig. 4. The annular socket in the face of the projection b³ is adapted to receive the end of the ball b⁵, provided with a cavity or recess b⁶ for the reception of the projecting teat b⁴, which latter is made annular 75 in form, so that the ball b⁵ may turn thereon as a center and at the same time turn in the annular groove or socket of the projection b³. The ball b⁵ is provided at its opposite end 80 with a recess b⁷, similar to b⁶, for the reception of a projecting teat or stem b⁸, extended from the center of the cup-shaped socket in a projection b⁹ on a ring b¹⁰, which is detachably secured to the rim b² of the plate or disk b' by suitable bolts b¹². The rim b² is provided with an annular channel or groove into 85 which the rim b⁹ fits, so that a flange c on the rim projects over the ring b¹⁰, and a plate c' may be secured to the framework of the machine and close the wheel and render it substantially dust-proof.

By reference to Figs. 3 and 4 it will be seen that the studs or teats b⁴ b⁸ act as centering studs or teats, and the annular sockets in the projections b³ b⁹ fit over and embrace the ends 95 of the balls b⁵, so that the latter are firmly held against dislodgment, and if for any reason the centering-teats b⁴ b⁸ should become broken the balls b⁵ would still be retained in their cup-shaped sockets and prevented from 100 dropping out of place, which would render the driving mechanism substantially useless.

The balls b^5 have coöperating with them a pinion c^3 , provided with rounded teeth c^4 and concavities c^5 , which engage the balls b^5 . The pinion c^3 is rendered fast on the counter-shaft a^2 in any suitable or desired manner, as by the screw c^6 , and the said shaft has fast on it the sprocket-wheel c^7 , which may be of any suitable or usual construction, about which is passed the link chain c^8 , which connects the sprocket-wheel c^7 with the sprocket-wheel on the shaft of the rear wheel A' . The disk wheel b' may have secured to or forming part of it one of the pedal-arms c^{10} , as shown in Figs. 2 and 3. In practice the projections b^3 , with their cup-shaped sockets and teats b^4 , may be forged or cast in one piece with the disk b' , and the latter may be made thin to insure lightness. So, also, the projections b^9 , having the cup-shaped sockets, may be made of one piece with the ring b^{10} .

I claim—

In a safety-bicycle, the combination with a pedal-shaft having bearings in the framework between the front and rear wheels of the said bicycle, a driving-wheel fast on the pedal-shaft consisting of the disk b' provided with an annular rim and on its inner face

with projections b^3 having in their faces ball-receiving sockets provided with projecting teats b^4 , a ring b^{10} secured to said disk and provided with projections having ball-receiving sockets provided with projecting teats b^8 , balls interposed between said disks and extended into the sockets of the said projections to be embraced by the same and provided at their opposite ends with sockets into which extend the projecting teats b^4 , b^8 and on which the said balls turn, a counter-shaft supported by the framework and extended into the driving-wheel, a pinion fast on the counter-shaft within the driving-wheel and meshing with the said balls, a sprocket-wheel fast on the counter-shaft, a sprocket-wheel fast on the rear wheel of the bicycle and a link chain connecting said sprocket-wheels, substantially as described.

In testimony whereof I have signed my name to this specification in the presence of two subscribing witnesses.

JOHN GOETTEL.
